UNITED STATES PATENT OFFICE.

EVELYN F. FRENCH, OF NEW YORK, N. Y.

DESIGN FOR A SEWING-MACHINE CASE.

SPECIFICATION forming part of Design No. 11,999, dated October 26, 1880.

Application filed June 17, 1880. Term of patent 14 years.

To all whom it may concern:

Be it known that I, EVELYN F. FRENCH, a citizen of the United States, residing in the city of New York, county of New York, and 5 State of New York, have invented and produced a new and useful Design for Sewing and other Machine Cases, of which the following is a specification, reference being had to the accompanying drawings, forming a part 10 thereof.

Figure 1 represents a perspective view of my newly-designed case. Fig. 2 represents a front view with an oval panel as a modification of the one shown in Fig. 1.

15 The leading features of my design consist in the rounded front and back top corners of the case or cover, (represented at A,) and a band, forming a base, which may partially or entirely surround the bottom part, as at B. (I 20 sometimes add a panel upon the front, as at C, and upon other sides when desirable, and I sometimes apply one upon the top, as represented at D, as may be desired.)

A represents the rounded corners of the 25 case or cover, and B the base, which, when

added, aids in perfecting the symmetry of the whole; and C, a panel projecting on the front, which may be varied in form—either oval, rectangular, elliptical, or otherwise.

D is a panel upon the top, the outlines of 30 which may be of any shape preferable, although it may be dispensed with altogether when desirable, and E is a lip projecting or overhanging the front and rear of the case or cover below the rounded corners, near the top, 35 substantially as shown.

Having thus set forth and illustrated my new and original design, I claim—

A design for sewing-machine covers and other objects, consisting of a flat top, D, 40 rounded upper edges, A, longitudinal beads E, vertical sides having panels C, the band B, passing around the bottom of the case or cover, and the corner ornaments, substantially as described.

EVELYN F. FRENCH.
